JAMES G. MACLAREN, OF HARRISON, NEW YORK.

PNEUMATIC-DESPATCH-TUBE APPARATUS.

1,346,042.

Specification of Letters Patent.

Patented July 6, 1920.

Application filed July 26, 1915. Serial No. 41,898.

To all whom it may concern:

Be it known that I, JAMES G. MACLAREN, of Harrison, in the county of Westchester and State of New York, have invented certain new and useful Improvements in Pneumatic-Despatch-Tube Apparatus, of which the following is a specification.

The main object of my invention is to produce a pneumatic despatch tube apparatus which will permit the use of a plurality of sending tube vacuum pressure transit tubes that may be operated independently of each other simultaneously or otherwise with only one exhauster and one compressor necessary for propulsion of carriers. These and other objects are carried out by the mechanism hereinafter described and shown in the drawings.

In the accompanying drawings which illustrate a construction embodying my invention:

Figure 1 is an assembly view mostly in section showing a dead line with parts in normal position and a sub station and central station for despatching and receiving carriers and transit tubing connecting them.

Fig. 2 is an enlarged sectional view of the central station terminal with parts in normal position.

Fig. 3 is an enlarged sectional view of parts of the central station terminal showing such parts in position they will occupy while a carrier is in transit from the sub station to the central station.

Fig. 4 is a view of a modification similar to Fig. 1, except that parts are in the position they will occupy when a carrier is in transit from the central station to the sub station.

Fig. 5 is a sectional view showing a carrier arriving at the sub station.

Fig. 6 is a sectional view showing a carrier starting from the sub station.

Fig. 7 is a sectional view showing the carrier in Fig. 6 arriving at the central station.

Like letters of reference refer to like parts throughout the several views.

The construction and operation of the apparatus will be clearly understood by a description of the insertion and transmis-

sion of a carrier from the sub station to the central station.

At the sub station S is located a receiving chute A carried at one end by the support A'. The other end is attached to a plate A² having an opening therein in alignment with the transit tube D to which it is connected by a coupling D'.

A carrier Y being inserted through the plate A² enters through a short section of transit tube D into a contactor B where it engages with a trip B' (Fig. 6) depressing and revolving same about pivot B². Attached to the pivot B² are rods B⁴ which move on pivots B³. The opposite end of rods B⁴ has attached thereto insulated disks B⁵. Trip B' is normally held in the position indicated in Fig. 1 by the spring B⁶ attached at one end to the main casting of contactor B and at the other to the trip B', as shown.

The carrier having engaged trip B' the parts will occupy the position indicated in Fig. 6, which results in the making of a contact between contact blades N' and N² which are supported in an insulator N.

The transit tube D continues as shown through central station contactor E, central station terminal F where the carrier will deliver. When air is in circulation from the sub station toward the central station said air will pass around the barrier or guide F⁴ into passage F⁶, tube G, tube H, through ports J² and passageway J³ of vacuum valve J through nipple V' into the vacuum drum V which is connected to a suitable exhauster common in the art which maintains in the vacuum drum V a predetermined working pressure below that of the atmosphere. The vacuum valve J is a balanced valve of suitable capacity and of ordinary construction operated by a solenoid or magnet coil a.

A carrier Y being in engagement with trip B', as above described, an electric circuit will have been completed starting with positive line 1, through wire 2, jack b⁸, plate b³, jack b⁷, wire 3, wire 4, wire 5, blade N', blade N², wire 6, coil a, wire 7, wire 8 to negative line 9, thereby energizing coil a.

which results in moving its core a' in an upward direction lifting valves J' , thereby opening an air passage from tube H through ports J^2 , passage J^3 and nipple V' into vacuum drum V , which results in a partial vacuum being formed in the transit tube D ahead of the carrier which will result in the atmospheric pressure propelling the carrier which upon reaching the central station contactor E engages with a trip E' in central station contactor E .

The core a' at its lower end is attached to the valve J' by a rod a^4 and from its upper end supports through an insulated rod a^2 the plate a^3 in contact with jacks a^5 and a^6 which results in closing a retaining circuit from positive line 1, through wire 2, wire 3, wire 4, jack a^5 , plate a^3 , jack a^6 , wire 10, contact blades O' and O^2 , wire 11, wire 6, coil a , wire 7, and wire 8, to negative line 9, thereby maintaining the vacuum valve J open until carrier reaches and engages with trip E' in its travel, as above described. When the carrier moves the trip E' the parts contained in central station contactor E will occupy the position shown in Fig. 7, as trip E' is free to revolve on pivot E^2 although normally held in the position shown in Fig. 1 by the spring E^6 . The rods E^4 are attached to the trip E' at pivots E^3 . One of the rods E^5 has attached to the end thereof an insulated disk E^5 arranged to engage with contact plate O' which is normally in contact with contact plate O^2 supported in insulator O . The retaining circuit last described having been opened between contact blades O' and O^2 the core a' and parts attached thereto will drop by gravity, thereby shutting off the connection between the transit tube and vacuum drum V by reason of valves J' sealing ports J^2 .

The central station terminal F , Fig. 2, has therein a coil F^8 contained in a cast iron coil yoke F^{12} for purposes hereinafter described. The coil F^8 terminates in poles F^{13} . The coil yoke F^{12} has therefrom a projection F^{11} to which is attached a leather hinge F^{10} which in turn is attached to a leather valve F' which normally, because of its weight, hangs in a position indicated in Fig. 2. It is held in an upward direction by the spring F^2 contained in the case F^3 . The vacuum valve J having been opened thereby creating a partial vacuum within the terminal F the atmospheric pressure will push the valve F' to its seat as indicated in Fig. 3, thereby sealing the interior of terminal F from the atmosphere, compelling the air to enter the line at the sub station end A^2 of the tube D .

The incoming carrier having engaged trip E' breaking the retaining circuit of coil a , as above described, destroying the partial vacuum within the terminal F leaves the carrier free to pass from the tube line D

into the terminal F and be discharged through valve F' .

For the return of a carrier from the central station to a sub station the valve F' is depressed manually and the carrier inserted 70 into the tube D through terminal F . The door F^7 is then raised manually and the push button L pressed thereby closing a circuit from positive line 1, through wire 2, wire 18, jack a^7 , plate a^8 , jack a^9 , wire 12, 75 wire 13, push button L , wire 17, wire 15, coil b and wire 8 to negative line 9, thereby energizing coil b lifting its core b' attached at its lower end through rod b^4 to valves K^2 , thereby opening the connections between 80 transit tube D and terminal F through passage F^6 , tube G , passage Q , ports K^2 , passage K^3 and nipple P' into pressure drum P and completing the retaining circuit which will keep the pressure valve K open, the retaining circuit starting from positive line 1 through wire 2, wire 18, jack a^7 , plate a^8 , jack a^9 , wire 12, wire 14, contact blades M' and M^2 , wire 19, wire 5, wire 4, jack b^9 , plate b^8 , jack b^5 , wire 15, coil b and wire 8 85 to negative line 9.

The carrier X will therefore be propelled toward the sub station S by the pressure existing between it and pressure drum P , said pressure drum P being supplied with 90 air from a compressor common in the art arranged to maintain a predetermined working pressure therein.

Upon the carrier X arriving in sub station contactor B the parts will occupy the positions shown in Fig. 5 and open the contact between contact blades M' and M^2 by reason of the carrier revolving the trip B' moving the rods B^4 to the position shown in Fig. 5 whereby one of the disks B^5 engages 100 with contact blade M' opening the retaining circuit last described thereby deenergizing coil b and permitting the core b' and the parts attached thereto to drop and thereby shut off the air connections between the 110 transit tube D and the pressure drum P by reason of the valves K' sealing the ports K^2 . The carrier is then free to pass from contactor B through plate e^2 and be brought to rest by suitable chute A .

The springs E^6 in contactors E and B are not of sufficient strength to impede the travel of the carrier.

The retaining circuit of coil b having been completed by the pressing of push button L there is placed in the circuit in multiple with said coil b the magnet coil F^8 , the circuit being completed from positive line 1, through wire 2, jack b^8 , wire 18, jack a^7 , jack a^8 , plate a^9 , and wire 12, wire 14, 120 contact blades M' and M^2 , wire 19, wire 5, jack a^5 , wire 4, jack b^9 , plate b^8 , jack b^5 , wire 20, coil F^8 , wire 16, and wire 8 to negative line 9.

The door F^7 being all iron serves as the 130

armature to the clutch magnet consisting of the coil F^8 and its cast iron yoke F^{12} it is therefore apparent that it will be retained on its seat and prevent the escape of air to the atmosphere from terminal F , the yoke F^{12} and door F^7 having finished surfaces; it is also evident that said door F^7 which pivots on F^9 will drop by gravity when the coil F^8 is deenergized by reason of the carrier arriving within contactor B and opening the retaining circuit of coil b and leaving line in normal position for use from either end.

In Fig. 4 is shown a modified construction. The despatching and receiving of carriers and electric circuits are identical with description heretofore given and for that reason is not repeated. The coils a and b which is Fig. 1 must be large enough to have sufficient capacity to lift the heavy valves J' and K' are replaced by the smaller coils c and d , and large main valves J and K are replaced by small pilot valves T^2 and W^2 , and large valve J is replaced by a valve Z containing a gate Z' to close the air passage by sealing the port Z^2 . The gate Z' is attached to the rod Z^5 which in turn is secured to a flexible diaphragm Z^4 secured to and sealing the underside of the case Z^8 forming an air chamber Z^6 . This chamber Z^6 is open to the atmosphere through a minute opening Z^7 and the lower side of the diaphragm Z^4 is exposed to the atmosphere. The chamber Z^6 communicates through pipe T^6 , valve T^2 and pipe T' to the tube T in which is maintained a partial vacuum. Within the valve T^2 is indicated a gate T^8 through which is a hole T^4 that may be placed in alignment with the pipes T' and T^5 thereby permitting the air to be exhausted from the chamber Z^6 more rapidly than atmospheric air is admitted through the opening Z' , thereby maintaining in the chamber Z^6 a pressure practically the same as in pipe T . The diaphragm Z^4 is of sufficient area to permit the atmospheric pressure on the underside of said diaphragm, when T^2 is open, to exert enough force to overcome the pressure on the gate Z' and lift same from its seat when the rod Z^5 and gate Z' will occupy the dotted positions Z^5 and Z^8 thereby setting up a circulation of air. The air from transit tube D will bypass through casting R , passages R' , R^2 , Z^8 , port Z^2 and nipple V' into vacuum drum V for the propulsion of the carrier from the substations to the central station C .

Pressure valve U has a gate U' controlling the port U^2 said gate U' being attached to the rod U^5 and flexible diaphragm U^4 covering the underside of casing U^8 said casing having a minute opening U^7 into the chamber U^6 in every way similar to the vacuum valve Z except that on opening the

pressure valve U the rod U^5 must be moved 65 in a downward direction to the position indicated in Fig. 4, and a spring U^9 is provided to return the rod U^5 to its normal position to close gate U' over port U^2 . The chamber U^6 is connected through a pipe W^6 , 70 pilot valve W^2 , and pipe W' to a pipe W in which is maintained an air pressure above that of the atmosphere. As indicated in Fig. 4 it is assumed that door F^7 has been closed for the transmission of a carrier 75 from the central station C to the sub station S and that the push button L has been pressed and released thereby having energized coil d as explained in the description of Fig. 1, and thereby completed the retaining circuit for coil d in a manner identical with that for coil b . The core d' carries the insulated rod d^2 which in turn supports the contact making plate d^3 to make contact across jacks d^7 and d^8 when in its lower 85 position. The core d' is attached to the gate W^8 by means of a rod d^4 . Jacks d^6 , d^7 , d^8 , d^9 , in Fig. 4 correspond with jacks b^5 , b^6 , b^7 , b^8 and b^9 respectively in Fig. 1. Core c' of coil c has attached to its upper end an 90 insulated rod c^2 supporting the contact plate c^3 which in its upper position will close contact across jacks c^5 and c^6 and which in its lower position will close contact across jacks c^7 and c^8 . Attached to the lower end of 95 core c' is a rod c^4 which in turn is attached to the gate T^8 of the pilot valve T^2 . The jacks c^5 , c^6 , c^7 and c^8 in Fig. 4 correspond with the jacks a^5 , a^6 , a^7 , and a^8 respectively in Fig. 1. It is therefore apparent that the 100 despatch of a carrier from the sub station will cause the energizing and the deenergizing of the coil c and opening and closing of the pilot valve T^2 and therefore the opening and closing of the main vacuum 105 valve Z and that the closing of push button L will energize the coil d which will be deenergized by the arrival of the carrier in the contactor E and therefore the opening and closing of the pilot valve W^2 and the main 110 pressure valve U . The modification in Fig. 4 has the advantage over the construction in Fig. 1 of preventing the carrier smashing through the terminal head F upon its arrival at the central station. The incoming carrier 115 when it engages with a trip E' opens the retaining circuit of the coil c , but the valve Z' cannot immediately return to its seat as its descent by gravity is governed by the amount of time required for the admission 120 of atmospheric air through a minute opening Z^7 into chamber Z^6 . The carrier having engaged trip E' and opened the retaining circuit, the circulation of air will continue for a short period and the carrier will 125 be slightly retarded in its travel through the casting R due to the friction created by the air draft from transit D and casting R .

into the passage R'. The carrier velocity and weight combined will carry it through casting R causing it to compress the air between the carrier and the valve F' which 5 will cause it to nearly stop and then descend slowly as the air is exhausted from the space between the incoming carrier and the valve F' around the clearance spaces existing between the carrier and the inner wall of the 10 transit tube and terminal head F, thereby bringing the carrier to rest on the valve F' where it will remain until the vacuum valve Z is closed when the carrier is free to drop by gravity through the valve F' of the terminal F. The slow closing of the valves Z 15 and U has a further advantage of eliminating sudden shocks to the suction and pressure pipes, blower and motor, as the air velocity and pressure will not change so suddenly as in the construction shown in Fig. 1, wherein the valves J and K close instantly when the electric retaining circuit is broken.

It will also be observed that the contact blades N' and N² in the contactor B may be 20 replaced by the contact points in a manually operated push button such as L, this push button to be located within reach of the operator at sub station S, it will also be noticed that when the contact plate used in connection 25 with any of the coils a, b, c, d, is in its upper position, it opens the circuit in which is contained its companion coil thereby forming an interlocking device which prevents the opening of the main vacuum valve 30 J while the pressure valve K is open and vice versa. Valves Z and U are subject to a similar control.

Having thus described the nature of my 35 invention and set forth a construction embodying the same, what I claim as new and desire to secure by Letters Patent of the United States, is:

1. In an apparatus of the character described, the combination of a pressure source 40 and a suction source, a single transit tube for the transmission of carriers in either direction from a central station to a substation and from the sub-station to the central station, a valve controlling the passage 45 of air from said transit tube to said suction source, a valve controlling the passage of air from said pressure source to said transit tube, electrically operated means for opening one of said valves to cause air to propel 50 a carrier from the sub-station to the central station, electrically operated means including a device in the path of the traveling carrier for causing such valve to close, electrically operated means to open the other 55 valve to cause air to propel a carrier from the central station to the sub-station, electrically operated means including a device in the path of the traveling carrier for causing the last-mentioned valve to close, and interlocking means for preventing the open- 60

ing of one of said valves when the other of said valves is open.

2. In an apparatus of the character described, the combination of a pressure source and a suction source, a single transit tube 70 for the transmission of carriers in either direction from a central station to a substation and from the sub-station to the central station, a valve controlling the passage of air from said transit tube to said suction source, a valve controlling the passage of air from said pressure source to said transit tube, electrically operated means including a device in the path of the inserted carrier 75 to open one valve to cause air to propel such carrier from the sub-station to the central station, electrically operated means including a device in the path of the traveling carrier for causing such valve to close, electrically operated means for opening the 80 other valve to cause air to propel a carrier from the central station to the sub-station, electrically operated means including a device in the path of the traveling carrier for causing the last-mentioned valve to close, 85 and interlocking means for preventing the opening of one of said valves when the other of said valves is open.

3. In an apparatus of the character described, the combination of a pressure source 90 and a suction source, a single transit tube for the transmission of carriers in either direction from a central station to a substation and from the sub-station to the central station, a valve controlling the passage 95 of air from said transit tube to said suction source, a valve controlling the passage of air from said pressure source to said transit tube, means for opening one of said valves to cause air to propel a carrier from the 100 sub-station to the central station, means including a device in the path of the traveling carrier adjacent to said central station automatically to close such valve on or about the time of the arrival of the carrier at said central station, electrical means for opening the other of said valves to cause air to propel a carrier from said central station to said sub-station, means including a device adjacent to said sub-station automatically to 110 close the last-mentioned valve on or about the time of the arrival of the carrier at said sub-station, and locking means for preventing the opening of one valve when the other valve is open.

4. In an apparatus of the character described, the combination of a pressure source and a suction source, a single transit tube for the transmission of carriers in either direction from a central station to a substation and from the sub-station to the central station, a valve controlling the passage 125 of air from said transit tube to said suction source, a valve controlling the passage of air from said pressure source to said transit tube, 130

- tube, means set in operation by a traveling carrier for opening one of said valves to cause air to propel a carrier from the sub-station to the central station, means set in operation by said traveling carrier for closing the said valve thus opened, means for opening the second valve to propel the carrier from the central station to the sub-station, means set in operation by a traveling carrier for closing the last-mentioned valve, and retarding means to delay the discharge of the carrier at the central station end of the transit tube when the closing means for said first-mentioned valve is operated.
5. In an apparatus of the character described, the combination of a pressure source and a suction source, a single transit tube for the transmission of carriers in either direction from a central station to a sub-station and from the sub-station to the central station, a valve controlling the passage of air from said transit tube to said suction source, a valve controlling the passage of air from said pressure source to said transit tube, electrically operated means for opening one of said valves to cause air to propel a carrier from the sub-station to the central station, electrically operated means including a device in the path of the traveling carrier for causing such valve to close, electrically operated means to open the other valve to cause air to propel a carrier from the central station to the sub-station, electrically operated means including a device in the path of the traveling carrier for causing the last-mentioned valve to close, and retarding means to delay the discharge of the carrier at the central station end of the transit tube when the closing means for said first-mentioned valve is operated.
6. In an apparatus of the character described, the combination of a pressure source and a suction source, a single transit tube for the transmission of carriers in either direction from a central station to a sub-station and from the sub-station to the central station, a valve controlling the passage of air from said transit tube to said suction source, a valve controlling the passage of air from said pressure source to said transit tube, electrically operated means for opening one of said valves to cause air to propel a carrier from the sub-station to the central station, electrically operated means including a device in the path of the traveling carrier for causing such valve to close, electrically operated means to open the other valve to cause air to propel a carrier from the central station to the sub-station, electrically operated means including a device in the path of the traveling carrier for causing the last-mentioned valve to close, interlocking means for preventing the opening of one of said valves when the other of said valves is open, and retarding means to de-
- lay the discharge of the carrier at the central station end of the transit tube when the closing means for said first-mentioned valve is operated.
7. In an apparatus of the character described, the combination of a pressure source and a suction source, a single transit tube for the transmission of carriers in either direction from a central station to a sub-station and from the sub-station to the central station, a valve controlling the passage of air from said transit tube to said suction source, a valve controlling the passage of air from said pressure source to said transit tube, means for opening one of said valves to cause air to propel a carrier from the sub-station to the central station, means including a device in the path of the traveling carrier adjacent to said central station automatically to close such valve on or about the time of the arrival of the carrier at said central station, means for opening the other of said valves to cause air to propel a carrier from said central station to said sub-station, means including a device adjacent to said sub-station automatically to close the last-mentioned valve on or about the time of the arrival of the carrier at said sub-station, and retarding means to delay the discharge of the carrier at the central station end of the transit tube when the closing means for said first-mentioned valve is operated.
8. In an apparatus of the character described, the combination of a pressure source and a suction source, a single transit tube for the transmission of carriers in either direction from a central station to a sub-station and from the sub-station to the central station, a valve controlling the passage of air from said transit tube to said suction source, a valve controlling the passage of air from said pressure source to said transit tube, means for opening one of said valves to cause air to propel a carrier from the sub-station to the central station, means including a device in the path of the traveling carrier adjacent to said central station automatically to close such valve on or about the time of the arrival of the carrier at said central station, means for opening the other of said valves to cause air to propel a carrier from said central station to said sub-station, means including a device adjacent to said sub-station automatically to close the last-mentioned valve on or about the time of the arrival of the carrier at said sub-station, interlocking means for preventing the opening of one of said valves when the other of said valves is open, and retarding means to delay the discharge of the carrier at the central station end of the transit tube when the closing means for said first-mentioned valve is operated.
9. A pneumatic apparatus for the trans-

mission of carriers comprising, in combination, a single transit tube for the transmission of carriers in either direction therein, a pressure source and a suction source, valve means controlling the communication between said tube and said sources, electrically operated means for operating said valve means to place said tube in communication with either of said sources to cause the propulsion of a carrier in either direction, and means working with each valve, effective when the valve is open to preclude energization of the operating circuit for the other, thereby to prevent interference with the transmission of the carrier by operation of said valve means.

10. A pneumatic apparatus for the transmission of carriers, comprising, in combination, a single transit tube for the transmission of carriers in either direction therein, a pressure source and a suction source, valve means controlling the communication between said tube and said sources, means for operating said valve means to place said tube in communication with either of said sources to cause the propulsion of a carrier in either direction, and retarding means for delaying the discharge of the carrier after such previously established communication has been discontinued.

11. In an apparatus of the character described, the combination of a source of oppositely acting pressures, a single transit tube for the transmission of carriers in either direction between a central station and a sub station, valves controlling the admission of said pressures to the tube respectively, an electric circuit for initially operating each valve, a connecting device moving with the valve and acting to close a retaining circuit, automatic means for interrupting said retaining circuit, the initial operating circuit for each valve passing through the connecting device of the other and being broken by movement thereof when that other valve is operated.

12. In an apparatus of the character described the combination of a transit tube to transmit a carrier, suction means in communication therewith to draw a carrier from a distant station to a nearer station, a valve controlling the passage of air from said tube to said means, electrically controlled means for holding open said valve after a carrier is introduced at said distant station, automatic means for releasing said electric control as the carrier approaches the nearer station and brake means retarding the response of the valve to such release.

13. In an apparatus of the character described the combination of a transit tube to transmit a carrier, suction means in communication therewith to draw a carrier from a distant station to a nearer station, a

valve controlling the passage of air from said tube to said means, pneumatic means for moving the valve, electrically controlled means for operating said pneumatic means to hold open said valve after a carrier is introduced at said distant station, automatic means for releasing said electric control as the carrier approaches the nearer station, said pneumatic means functioning in the manner of a dash-pot to retard the response of the valve to such release.

14. In an apparatus of the class described a transit tube having a downwardly directed end portion closed by a terminal valve, a suction tube entering the pipe at a distance from the end, a valve controlling the pressure in said pipe, means for holding open the valve while a carrier is in transit toward said end, automatic means for releasing said valve as the carrier approaches the suction tube, and means for retarding the closing of the valve on release thereof.

15. In an apparatus of the character described, the combination of a pressure source and a suction source, a single transit tube for the transmission of carriers in either direction from a central station to a sub-station and from the sub-station to the central station, a valve controlling the passage of air from said transit tube to said suction source, a valve controlling the passage of air from said pressure source to said transit tube, means for opening one of said valves to cause air to propel a carrier from the sub-station to the central station, means set in operation by said traveling carrier for closing the said valve thus opened, means for opening the second valve to propel the carrier from the central station to the sub-station, means set in operation by a traveling carrier for closing the last-mentioned valve, and retarding means acting on the first mentioned valve to delay the discharge of the carrier from the central station end of said transit tube after the closing means for the valve is operated.

16. In an apparatus of the character described, the combination of a pressure source and a suction source, a single transit tube for the transmission of carriers in either direction from a central station to a sub-station and from the sub-station to the central station, a valve controlling the passage of air from said transit tube to said suction source, a valve controlling the passage of air from said pressure source to said transit tube, electrically operated means to open one valve to cause air to propel such carrier from the sub-station to the central station, electrically operated means including a device in the path of the traveling carrier for causing such valve to close, electrically operated means for opening the other valve to cause air to propel a carrier

from the central station to the sub-station, electrically operated means including a device in the path of the traveling carrier for causing the last-mentioned valve to close, 5 and retarding means acting on the first mentioned valve to delay the discharge of the carrier from the central station end of

said transit tube after the closing means for the valve is operated.

In testimony whereof, I have signed my 10 name to this specification this twenty-second day of July, A. D. 1915.

JAMES G. MACLAREN.
